UNITED STATES PATENT OFFICE.

PETER RUNKEL, OF NEUWIED, GERMANY.

FEED-REGULATOR FOR COFFEE, SPICE MILLS, AND THE LIKE.

1,076,153.

Specification of Letters Patent.

Patented Oct. 21, 1913.

Application filed October 19, 1911. Serial No. 655,551.

To all whom it may concern:

Be it known that I, PETER RUNKEL, merchant, a subject of the King of Prussia and German Emperor, residing at Neuwied-on-the-Rhine, in the Kingdom of Prussia and German Empire, have invented certain new and useful Improvements in Feed-Regulators for Coffee, Spice Mills, and the like, of which the following is a specification.

10 My invention relates to improvements in hoppers for coffee, spice-mills or the like and has for its object a feed-regulator for hoppers of this kind, the new arrangement being such that the hopper has a vertical 15 partition forming two chambers or compartments therein; and pivoted to the lower end of said partition is a valve or flap which, on being turned about its fulcrum by means of a handle arranged at the outside 20 of the hopper, can be so adjusted as either to close at the bottom completely or but partially either one of the two chambers or compartments formed by said vertical partition. Thus, when one of the two chambers or compartments is completely closed, only one material, for example coffee, contained in the other chamber or compartment is fed by 25 the action of its own weight to the grinding mill. If, however, said valve or flap is only partially closed, *i. e.* to a greater or 30 smaller extent, two different materials, for example coffee and a coffee surrogate contained separately in said two chambers or compartments will be fed at once, in the desired mutual proportion depending on the 35 position of the valve or flap with regard to said grinding mill. Further, according to the present invention said pivoted valve or flap is provided at its lower end with serrations or cutting projections adapted to 40 contact with, and to crush, material passing between the edges of said serrations or cutting projections and the outer wall of said hopper. By this arrangement the objection 45 is remedied, which consists therein that, when coarse-grained or similar material is to be ground and the position of the valve or flap needs to be adjusted or regulated accordingly, it often happens that, on account 50 of the resistance offered by the material squeezed between the valve or flap and the

wall of the hopper, the valve or flap cannot be displaced without a relatively great effort upon the handle provided for the adjustment of said valve or flap having to be 55 exerted. Now, owing to the present arrangement, said material squeezed between the valve or flap and the wall of the hopper is very easily crushed or comminuted by the serrations or cutting projections of said 60 valve or flap.

The accompanying drawing forming a part of this specification represents an embodiment of the invention.

Figure 1 is a front view of the device, 65 Fig. 2 a side-view, Fig. 3 a section on line B-B of Fig. 1, Fig. 4 a plan of Fig. 2.

The preferred form of a feed-regulator for a mixing-mill for coffee, spice or the like comprises a reservoir or hopper *a* divided into two chambers or compartments by a vertical partition *b*; *c* is the grinding mill. Over said grinding-mill *c* a valve or flap *e* is fitted on an axle *d*, by means of which either chamber or compartment of 70 the reservoir or hopper *a* can be more or less closed for regulating the feed, *i. e.* producing different mixtures. To the axle *d* a handle *f* is attached. A spring *h* serves by means of its tension to maintain the 75 valve or flap *e* in any adjusted position. Said valve or flap *e* is toothed or sharpened at its free edge, so that by means of the teeth, serrations or cutting projections, on the handle *f* being turned, any material, 80 which, while being ground, gets in front of the valve or flap, will be crushed, whereby the tight closing of the valve or flap is rendered possible. By means of a scale *g* arranged below the handle *f*, the proportion 85 of the mixture may be indicated.

Under the grinding-mill *c* is located the receiver or collector *s* for the final mixture.

Should the handle *f* be turned in the direction *k*, the valve or flap *e* assumes a position *l*, as shown in Fig. 1 in dotted lines, and the compartment on that side of the reservoir or hopper *a* is closed.

Having thus described my invention, what I claim and desire to secure by Letters Patent of the United States is:—

A hopper having a vertical partition

forming chambers therein and a valve pivoted at its upper end to the lower end of said partition and provided at its lower end with serrations or cutting projections adapted to contact with, and to crush, material passing from said chambers between said edge and the outer wall of said hopper.

In testimony whereof I affixed my signature in presence of two witnesses.

PETER RUNKEL.
